(57) **CLAIM**

We claim the ornamental design for the solar charger, as shown and described.

DESCRIPTION

FIG. 1 is a top plan view of our design for a solar charger.

FIG. 2 is a left side elevation view of FIG. 1.

FIG. 3 is a right side elevation view of FIG. 1.

FIG. 4 is a front elevation view of FIG. 1.

FIG. 5 is a back elevation view of FIG. 1.

FIG. 6 is a bottom plan view of FIG. 1; and,

FIG. 7 is a top perspective view of FIG. 1.

The broken lines shown represent unclaimed subject matter and form no part of the claimed design.
